(57) **CLAIM**

The ornamental design for a textured fiber cement cladding panel, as shown and described.

DESCRIPTION

FIG. 1 is a front perspective view of a textured fiber cement cladding panel embodying our new design;

FIG. 2 is a front view of the textured fiber cement cladding panel of FIG. 1;

FIG. 3 is a left side view of the textured fiber cement cladding panel of FIG. 1, the right side being a mirror image thereof;

FIG. 4 is a top view of the textured fiber cement cladding panel of FIG. 1, the bottom being a mirror image thereof; and,

FIG. 5 is an enlarged front view of the claimed portion of the textured fiber cement cladding panel of FIG. 1.

The back surface of the textured fiber cement cladding panel is not shown because it is flat and free of ornamentation and forms no part of the claimed design. The portions of the textured fiber cement cladding panel outlined in dash-dot broken lines in FIGS. 1-4 form no part of the claimed design in those figures.
